UNITED STATES PATENT OFFICE.

ROBERT CLOUGH CLARK, OF WINNIPEG, MANITOBA, CANADA.

ROOFING-CLIP.

1,297,323.

Specification of Letters Patent. Patented Mar. 18, 1919.

Application filed November 21, 1917. Serial No. 203,162.

To all whom it may concern:

Be it known that I, ROBERT CLOUGH CLARK, of the city of Winnipeg, in the Province of Manitoba, Canada, have invented 5 certain new and useful Improvements in Roofing-Clips, of which the following is the specification.

The invention relates to improvements in roofing clips and the principal object of the 10 invention is to provide a clip for nailing down sheet roofing which will effectively hold down the edges of the roofing and which is constructed to prevent the accumulation of water around the nail holes made 15 by the nail fastening the clip to the roof.

A still further object is to construct a clip from wire so that it can be readily manufactured and further to arrange it so that a wide bearing surface is provided in locations such as at the corners of the roofing 20 sheets.

With the above objects in view the invention consists essentially in a length of wire fitted throughout its length with spaced 25 loops and having the ends thereof coiled, the parts being arranged and constructed as hereinafter more particularly described and later pointed out in the appended claims, reference being had to the accompanying drawing in which:—

Figure 1 represents part of a roof with my clip applied on the sheeting and partially nailed.

Fig. 2 represents an enlarged detailed vertical sectional view through the roof showing my appliance in use.

Fig. 3 represents an enlarged plan view of a fragmentary portion of one of the clips.

Fig. 4 represents a side view of the same.

Fig. 5 represents a plan view of a modified construction of the clip.

Fig. 6 represents a side view of another modified construction of the clip.

In the drawing like characters of reference indicate corresponding parts in the several figures.

1 represents the usual roof board on which the roofing sheets 2 are applied with the lower edges of the upper sheets overlying

the upper edges of the lower sheets and 50 with the ends of the adjacent sheets butted together.

In order to make the invention clear I may say that these roofing sheets are customarily formed from a rubber and tar composition and are fastened to the roof by 55 nailing.

My clip, utilized in fastening sheets is now described.

It comprises a length of wire 3 fitted at 60 intervals throughout its length with loops 4 adapted to receive the nails and having the extremities terminating in end coils at 5 and 6. At this point I wish it to be noticed that the coils and loops all turn in 65 the same direction and are contained in the same plane so that when the strip is applied on the roof the coils and loops all face upwardly toward the peak of the roof or in 70 a direction away from the edge of the sheet 75 on which they are applied. These long strips are laid on the overlapped edges of the sheeting a short distance above the lower edge of the top or overlying sheet and they are nailed to the roof by nails 7 inserted at the loops and having heads sufficiently large 80 to cover the opening in the loops when the nails are driven home. It is desirable in utilizing these strips to have them long enough so that the coiled ends thereof lie 85 at the corners of the applied sheeting, as the coils give increased bearing surface to hold the corners of the sheeting from turning up and they also prevent the possibility of the sheeting being punctured by the strips.

Obviously when the clip has been applied, it holds the edge of the sheeting tightly down preventing curling at the edge and the consequent damaging effects of wind and 90 rain. Further it will be seen that the loops give a large bearing surface around the nail thereby preventing tearing at the nail and that when the nail is driven tightly home there is no possibility of leakage of water 95 to the nail holes in a location between the loop and the sheeting or between the head of the nail and the loop. Short lengths of

clips can be applied at the ends of the sheeting as shown at 8 and 9 in Fig. 1.

In the modified form of strip shown in Figs. 5 and 6, the loops are formed by making one complete turn of the wire.

What I claim as my invention is:—

A roofing clip comprising a length of wire fitted throughout its length with spaced loops and having the loops all turned in the

same direction and having the extremities 10 thereof terminating in coiled ends.

Signed at Winnipeg, this 27th day of October, 1917.

ROBERT CLOUGH CLARK.

In the presence of—

GERALD S. ROXBURGH,
W. BOGESS.
